UNITED STATES PATENT OFFICE

ELWIN H. KIDDER, OF CHICAGO, ILLINOIS, ASSIGNOR TO LINK-BELT COMPANY, OF CHICAGO, ILLINOIS, A CORPORATION OF ILLINOIS

CLAMPING AND PLATFORM LOCKING MECHANISM

Application filed April 29, 1929. Serial No. 358,863.

This invention relates to a platform lock for car dumpers or unloaders. It has for one object to provide an automatic lock which will hold the car dumper against accidental displacement when the clamps are in their withdrawn or depressed position. Another object is to provide such a lock which is automatic in response to movement of other parts of the carrying and dumping assembly. 6 Another object is to provide such an end locking device which will automatically lock and unlock the ends of the car supporting platform in response to the movement of the car engaging members such as clamps. Other objects will appear from time to time in the course of the specification and claims.

The invention is illustrated more or less diagrammatically in the accompanying drawings wherein:

20 Figure 1 is a vertical cross section showing the car dumping mechanism generally in elevation; Figure 2 is a longitudinal vertical cross section taken on a reduced scale at line 2—2 of Figure 4 and showing in addition the end clamp and some of the associated parts;

25 Figure 3 is a detailed elevational view on an enlarged scale with parts broken away and parts in section showing one of the locks;

30 Figure 4 is a transverse vertical cross section taken on line 4—4 of Figure 3;

Figure 5 is a transverse vertical cross section taken on line 5—5 of Figure 3;

35 Figure 6 is a longitudinal horizontal cross section taken on line 6—6 of Figure 3.

Like parts are designated by like characters throughout the specification and drawings.

40 A indicates generally walls and foundations which define and inclose a pit A¹ within which the dumping mechanism is mounted.

B is a cradle carried on pairs of wheels B¹ which are themselves pivotally supported in frame members B² which are pivotally supported as at B³ upon foundations B⁴. The cradle is given an endwise tipping movement by means of a cable B⁵ which is attached to the cradle at either end as at B⁶, B⁷ and is driven by a rotating or driving assembly B⁸. B⁸ is a solenoid brake mechanism which holds the cradle in any dumped position.

These parts will not be further described as their details form no particular part of the present invention, since the brake may be applied to many different sorts of car dumping assemblies.

55 A car carrying platform C is positioned and movably supported upon the cradle mechanism. It is adapted to carry rails C¹ upon which a car C² may be supported. The car platform is positioned within the cradle assembly for relatively side-wise tilting movement. It is supported in the assembly upon bearings C³, C⁴ and is adapted to be tilted by a mechanism indicated generally at C⁴. The details of this mechanism form no particular part of the present invention as the lock of the invention can be applied to the mechanism no matter what the particular form of side-tipping arrangement. C⁵, C⁶ are end supporting posts carried upon foundations C⁶, C⁶. These supporting posts are preferably arranged on the side opposite that towards which the car is to be dumped when it is tilted side-wise. The two end locks which will be described below are positioned on the dumping side,—that is to say, the side towards which the car and supporting frame are arranged to dump and they serve particularly to carry the weight of a car or locomotive which may move upon or pass over the dumper.

70 In the car supporting frame which is designated generally by the letter C, preferably at either end of that frame, is mounted a clamp or combined clamp and clamp carriage. These serve to clamp the car on the car supporting platform to prevent accidental slipping or movement of it and to center it on the platform. D indicates the clamp carriage generally. It is provided at one end with a clamp member D¹ adapted to contact or engage the car and preferably the car coupler. D² is a track mounted within a cavity D³. D⁴ is a continuation of the track D². It is mounted on the car supporting frame and serves to carry the clamp and clamp carriage when the latter is in the raised or clamping position. D⁵, D⁶ are rollers positioned on the clamp carriage and adapted to run upon the tracks D², D⁴.

Mounted below the tracks D⁴ and supported also on the platform C is a track D⁶. D⁶ is a shaft pivotally attached as at D⁹ to the end of the clamp carriage. It is provided with a roller D⁷ which is adapted to run along the track D⁶. The shaft D⁸ is threaded throughout the major portion of its length as shown, and engages a nut not shown, which is positioned within the housing D¹⁰. The nut is adapted to be rotated by means of a gear D¹¹ which is itself driven by a gear D¹² carried on a shaft D¹³. At its outer end the threaded shaft D⁸, D⁸ carries a guide supporting member D¹⁴. The shaft D¹³ is driven by a motor D¹⁵. D¹⁶ is a laterally extending member positioned on the clamp carriage D. D¹⁷, D¹⁷ are inverted tracks or track members supported generally on the platform C. D¹⁸, D¹⁸ are lateral projections formed on the clamp carriage and adapted to engage the track members D¹⁷. They assist in preventing displacement of the clamp carriage. Each clamp D carries a roller D²⁰, the purpose of which will be later described.

F is a shaft journaled in bearings in the frame C and carrying a crank member F¹ which has attached to its one end a link F² which is movably joined to a locking latch F³. This latch is supported and guided in members F⁴, F⁴ which are themselves also supported on the platform C. Stops F⁵, F⁶ are positioned on the locking latch F³. Fixed also on the shaft F is a double cam member having two cam projections or noses F⁷, F⁸ and a lever-like extension F⁹. Mounted in the end of this extension is a rod F¹⁰ which passes through a member F¹⁵ of the frame C and carries at its outer end an adjustable locking nut F¹¹ and a washer or other laterally extending member F¹². F¹³ is a member generally similar to the member F¹² and contacts projections F¹⁴ which are fixed on the I-beam F¹⁵ through which the rod F¹⁰ passes. Between the members F¹³ and F¹² is a spring F¹⁶.

G is a member supported from the foundation A and lying within the cavity B³. It is slotted as at G¹ and provided with a reinforcing member G² which lies about the slot and is shaped as at G³ to serve as a guiding member. The outer end or nose of the locking latch F³ may penetrate within the slot G¹ as indicated particularly in Figure 6 and also shown in Figure 3.

It will be realized that while I have shown and described an operative device, many changes may be made in the size, shape, relation and proportion and distribution of parts without departing materially from the spirit of my invention, and I wish, therefore, that my description and showing be considered as in a large measure diagrammatic.

The use and operation of this invention are as follows :

The parts are normally assembled as shown

in Figure 1 in which the pit is provided and within which the dumping mechanism is positioned and supported upon suitable foundations. The dumping mechanism comprises generally a cradle as shown, and means for moving it so as to tilt the car longitudinally. Within the cradle is a movably positioned car supporting platform which is adapted to tilt the car laterally. In the form shown the dumping mechanism has positioned with it a grain door opening mechanism. The particular details of this are shown only generally and are not described, since the dumping mechanism may be used for other purposes. The general effect of the grain door opener is to position at a certain grain door and to provide for the disposal of the grain which is dumped from the car. This tipping equipment, however, may be used in connection with many other types of cars and for many other purposes.

In operation, a car is run upon the car supporting platform and after it is in position the clamping carriages are operated so that they rise from their withdrawn position of Figure 2 into their engaged position shown in Figure 1. In this engaged position as shown in Figure 1, the clamps D¹ are in contact with the couplers of the car and hold the car against movement and center it on the supporting platform. The locking mechanism is operated in response to movement of the clamping carriages. When the clamping carriages are in the position shown in Figure 2, that is to say, when they are completely withdrawn and do not engage or extend into the path of a car, the locks are automatically thrown into the locking position shown in Figure 3. In this locking position they are in engagement with the fixed members which form part of the assembly and of the support on the fixed foundations. As the carriages are moved into the clamping position the locks are operated and withdrawn from engagement so that they assume the disengaged position of Figure 1 when the car is properly held by the clamping means. Then the car carrying assembly is free to rotate. The operation of the locks is as follows: The lock mechanism is shown in detail in Figures 2 and 3. Assuming the lock to be in the engaged position as shown in detail in Figure 3, the spring F¹⁶ is under compression and exerts a pull on the rod F¹⁰ which is communicated to the portion F⁹ of the cam, and since this pull is below the center of the shaft F upon which the cam is mounted, it tends to hold the cam in the position which it occupies at the time, namely in the locking position, which causes the lock F³ to be thrust forward into engagement with the members G, G², as shown, through the slot G¹. When now, a car has been brought upon the car receiving platform and it is desired to fasten it in place, the driving mechanism D¹⁵ 130

is put into operation and then through the linkage shown the nuts within the casing D¹⁰ are rotated and move the threaded shaft D⁸ inwardly from the position shown in Figure 2 to the position shown in Figure 1. As they move inwardly, guided by the tracks D², D⁴ and D⁶, the roller D²⁰ comes in contact with the cam portion F⁷ and striking it, engages for a brief period and as the movement of the shaft D⁸ is continued, the roller D²⁰ carries the cam F⁷ along with it and so rotates the cam as a whole into the position shown in Figure 1 and in the dot and dash line of Figure 3. As this takes place the rod F¹⁰ is of course moved from the dotted line position shown in Figure 3 to the dot and dash position of Figure 3. The spring F¹⁶ is under an initial compression which increases somewhat as the rod F¹⁰ is moved beyond the center of the shaft F. The compression in the spring, however, produces sufficient tension on the shaft F¹⁰ to hold the cam and of course the latch F³ either in the locked or the unlocked position. After the car has been tipped and it is desired to remove it from the platform, the driving mechanism D¹⁵ is operated in a reverse direction and thus the nuts engaging the shafts D⁸ are rotated in a reverse direction and the shafts are moved from the unlocked position shown in Figure 1 to the outer or locked position shown in Figure 3, and the clamp carriages move out of engagement with the car and into the position shown in Figure 2. As this operation takes place, the roller D²⁰ contacts the cam part F⁸ and carries it from the dot and dash position indicated in Figure 3 back again into the dotted position of Figure 3, which is also shown in full lines in Figure 2. Thus the movement of the clamping carriages automatically operates the latch controlling mechanism so that as the clamps move into the car engaging position, they unlock the latches or withdraw them from engagement and as the clamping carriages move again to the disengaged position, they automatically move the latches to engage the fixed parts on the foundation and to hold the car supporting platform from further movement so that the car may be thereafter removed without any danger of accidental movement or displacement of the supporting frame.

I claim:

1. The combination in a car tipping assembly of a car carrying member, means for clamping the car in position thereon, locking means for the car supporting means, said locking means adapted to be moved by the said clamps during a part only of the motion of said clamps.
2. The combination in a car tipping assembly of a car carrying member, means for clamping the car in position thereon, locking means for the car supporting means,

said locking means adapted to be moved by the clamps during a part only of the motion of said clamps whereby when the clamp mechanism is in the inoperative position the latch is in its engaging position and when the clamp operating mechanism is in the operative position, the latch is disengaged.

3. In combination with a car tipping assembly, including means for supporting a car and for tipping the same, longitudinally and laterally, a plurality of clamping members mounted on the car support, means for operating them to clamp the car in position thereon and locks movable automatically in response to a part only of the movement of such clamping means to hold the car support in fixed position when the clamps are disengaged, and to free the car support after the clamps become engaged with the car.

4. In combination in a car tipping assembly, a car support, clamps movably positioned upon said support, means for moving them into and out of engaging position, a locking mechanism adapted to prevent the movement of the car support when engaged, an operating mechanism for said locking mechanism, including a swinging member, a part on said clamps adapted to contact said swinging member to operate the locking mechanism.

5. In combination in a car tipping assembly, a car support, clamps movably positioned upon said support, means for moving them into and out of operative position, locking mechanisms adapted to prevent the movement of the car support when engaged, operating mechanisms for said locking mechanisms including swinging members, a part on said clamps adapted to contact said swinging members to operate said locking mechanisms whereby said swinging members are moved in automatic response to movement of the clamps to cause unlocking when the clamps are in engagement with a car and to cause locking when the clamps are disengaged and moved toward the inoperative position.

6. In combination in a car tipping assembly, a movably mounted car support, clamps movably positioned upon said support, means for moving them into and out of engaging position, a locking mechanism including a latch and adapted to prevent movement of the car support when said locking mechanism is engaged and an operating mechanism for said locking mechanism, said operating mechanism including a pivoted member mounted on the car support and connected to said latch, said member provided with a part adapted to be contacted and moved by the clamp when the latter moves into the clamping position.

7. In combination in a car tipping assembly, a movably mounted car support, clamps movably positioned upon said support, means for moving them into and out of engaging position, a locking mechanism including a

latch and adapted to prevent movement of the car support when said locking mechanism is engaged and an operating mechanism for said locking mechanism, said operating mechanism including, a pivoted member mounted on the car support and connected to said latch, said member provided with a part adapted to be contacted and moved by the clamp when the latter moves out of the clamping position.

8. In combination in a car tipping assembly, a movably mounted car support, clamps movably positioned upon said support, means for moving them into and out of engaging position, a locking mechanism including a latch and adapted to prevent movement of the car support when said locking mechanism is engaged and an operating mechanism for said locking mechanism, said operating mechanism including a pivoted member mounted on the car support and connected to said latch, said member provided with a part adapted to be contacted and moved by the clamp when the latter moves into the clamping position, and means for retaining the last mentioned operating mechanism in whichever position it may occupy until it is again contacted by the clamp.

9. In combination in a car tipping assembly, a movably mounted car support, clamps movably positioned upon said support, means for moving them into and out of engaging position, a locking mechanism including a latch and adapted to prevent movement of the car support when said locking mechanism is engaged and an operating mechanism for said locking mechanism, said operating mechanism including a pivoted member mounted on the car support and connected to said latch, said member provided with a part adapted to be contacted and moved by the clamp when the latter moves out of the clamping position, and means for retaining the last mentioned operating mechanism in whichever position it may occupy until it is again contacted by the clamp.

Signed at Chicago, county of Cook and State of Illinois, this 8th day of April, 1929.
ELWIN H. KIDDER.
